BEVERAGE DISPENSING DEVICE

Filed Aug. 31, 1929

UNITED STATES PATENT OFFICE

JOHN THOMSON AND JOHN LANGFELDER, OF BUFFALO, NEW YORK

BEVERAGE DISPENSING DEVICE

Application filed August 31, 1929. Serial No. 389,828.

Our invention relates to new and useful improvements in beverage dispensing devices; and has more particular reference to devices for dispensing carbonated or charged beverages, such as ginger ale and the like.

Carbonated or charged beverages are invariably kept in cellars or elsewhere in supply containers subjected to a pressure upward of eighty pounds per square inch, and it is necessary to reduce this to approximately eight or ten pounds before dispensing in serving glasses or other vessels. A pressure upward of eighty pounds per square inch is believed necessary in supply containers in order to keep the beverage in properly charged condition so as to retain the life and sparkle so highly desirable; but the dispensing of the beverage into serving glasses or other vessels at such a high pressure is impossible, since the beverage would be dispensed in substantially spray form and be converted into a light foamy substance and it would also spurt over the edges of the glasses or other vessels when dispensing the beverage into them.

It is, therefore, necessary to reduce the pressure under which the beverage is dispensed; but dispensing should take place under a pressure which will assure retention of the life and sparkle, and yet be dispensed with slight effervescence so that a light foamy top or collar appears at the top of a clear sparkling body while and directly after filling a glass or other vessel, such light foamy top lending attractiveness to the beverage and imparting life and sparkle to the same.

One of the objects of our invention is the provision of an auxiliary or dispensing chamber into which a quantity of the beverage is delivered under high pressure and which includes means to regulate the pressure at which the beverage is dispensed.

Another object is the provision of an auxiliary or dispensing chamber of the kind mentioned which can be retained in an ice or other refrigerating chamber to keep a quantity of the beverage at the desired low temperature preparatory to dispensing the same in still smaller quantities.

A further object is the provision of an auxiliary or dispensing chamber of the kind

last-mentioned which has conduit connection with a considerably larger supply container in which the main beverage supply is maintained under high pressure and from which the beverage is fed into the auxiliary or dispensing chamber in the exact proportion it is dispensed from said last-mentioned chamber.

A still further object is to provide new and novel means for regulating the admission of the beverage from the supply into the dispensing chamber and the discharge of the beverage therefrom; and also to permit of varying the pressure under which the beverage may enter and be discharged from said dispensing chamber.

With the above and other objects in view to appear hereinafter, our invention consists in the arrangement and in the combination of parts; and in the novel features of construction to be hereinafter described and more particularly pointed out in the subjoined claims.

In the drawing,—

Fig. 1 is a vertical section through our improved dispensing tank.

Fig. 2 is a cross section, taken on line 2—2, Fig. 1.

Fig. 3 is a cross section, taken on line 3—3, Fig. 1.

Fig. 4 is an enlarged cross section, taken on line 4—4, Fig. 1.

Our improved dispensing apparatus comprises a suitable dispensing chamber provided with a beverage inlet adapted for conduit connection with a supply container or storage tank having several times the capacity of said dispensing chamber, and with an outlet having conduit connection with a dispensing faucet which may be at some distance from said outlet, and regulating means

for controlling the admission of the charged beverage to said dispensing chamber, and the discharge of the beverage therefrom under considerably reduced pressure.

Reference being had to the drawing in detail, the numeral 5 designates a chamber which may have any capacity; it being preferably cylindrical in cross section closed at the bottom and open at the top. This chamber

may be constructed of any desired sheet material and at its upper end it has secured thereto in any approved manner a cast and machined collar 6 provided with rabbets 7, 8, at 5 its upper and lower sides, respectively, and along its inner circular edge, to form an inwardly-directed flange 9 which lies against and extends inwardly beyond the edge of the cylindrical sheet metal wall of the chamber.

10 Thus the upper end of the chamber is fitted into the lower rabbet 8 of the collar 6. At the lower end of this chamber a clean-out valve 10 is provided which permits the chamber to be easily cleaned by flushing 15 through the upper open end of the same.

A head or cover member 11 is provided to close the upper open end of the chamber and it comprises a flat member 12 provided with a hollow upward extension or hood 13 and 20 an axially-disposed bellows chamber 14 having its upper portion disposed in said upward extension or hood and its lower portion extending into the upper end of the chamber 5, which we term a dispensing 25 chamber, by reason of the beverage being dispensed therefrom; and which may also be termed an auxiliary chamber, due to the fact that it must be connected with a supply or storage chamber or tank in order to receive 30 the beverage preparatory to dispensing the same as called for.

The flat member 12 of the head or cover member has an annular flange or rib 15 on its under side which fits into the upper rabbet 35 7 of the collar 6; and the joint between the head or cover member 11 and the collar 6 may be machined water-tight or made so by the use of gaskets, or otherwise. Screws 16 or other suitable fastening means are employed for securing the head or cover member to said collar.

The upward extension or hood 11 of the head or cover member has a cylindrical wall 17 rising from the flat member 12 and a top 40 wall 18 provided centrally with a screw-threaded opening 19. The bellows chamber 14 has its upper end spaced from the top wall of the hood and it is supported by the cylindrical wall of the hood 13. The top 45 wall of said chamber is open, except for a flange 50 extending inwardly from the upper end of its peripheral wall 21.

The means provided for supporting the bellows chamber 14, which serves also as an 55 air-outlet chamber, is in the form of a boss 22 cast integral with said bellows or air-outlet chamber and said hood and spanning the space 23 between the peripheral walls of both. An outlet opening 24 is formed 60 through this boss and extends through the peripheral walls of both the bellows or air-outlet chamber and the hood and its outer end is screw-threaded to receive a nipple 25 to which an air-outlet pipe may be secured. 65 Said air-outlet pipe (not shown) may be led

to any desired point, outside of the building or otherwise, and by reason of its connection with the interior of the dispensing chamber, through the medium of the air-outlet chamber 14 and attached parts, permits the escape of air from the dispensing chamber under pressure above that intended to be maintained with said dispensing chamber.

The peripheral wall of the bellows or air-outlet chamber is also joined at other points around its circumference with the base of the hood 13 by means of spaced connecting webs 26. The bottom 27 of the bellows or air-outlet chamber is preferably a separate member, 70 threaded onto the lower end of the peripheral wall of said chamber, and it has a depending circular baffle flange 28 and an axial externally screw-threaded boss 29 extending downwardly therefrom, which boss has a reduced 75 end portion 30, serving as a valve seat as will presently appear.

An air-inlet passage 31 is formed through the bottom 27 of the bellows or air-outlet chamber and through the boss 29 and reduced end portion or extension 30 of said boss; said reduced end portion or extension 30 being therefore in the form of an annular flange depending from the boss 29, and the lower edge-face thereof serves as a valve seat for a 95 valve 32 disposed in a valve cage 33 suspended from said boss.

The valve cage 33 is in the form of a hollow cylindrical member open at its upper end and closed at its lower end and it has an 100 integral guide sleeve 34 depending axially from said closed lower end. The upper end of said hollow cylindrical member is internally screw-threaded and fitted onto the externally screw-threaded boss 29 and its peripheral wall is provided with a plurality of air-inlet openings 35.

The valve 32 comprises a metallic or other suitable head or body portion 36 of somewhat larger diameter than the valve seat on the 110 extension of the boss 29, and it has upstanding clench lips 37 spaced around its marginal portion, which are bent over and firmly hold a leather or other suitable valve disk 38 against the upper side of said valve head or body portion.

39 designates a float which is fastened to the lower end of a valve rod 40 screw-threaded at its upper end into or otherwise fastened to the head or body portion of the valve 32, 120 and guided for movement in the guide sleeve 34.

When the dispensing chamber 5 is empty or when containing a quantity of the beverage at a level below normal, the float will 125 be suspended in a fixed position by the valve 32, which latter under such conditions, rests against the bottom of the valve cage and causes the air-inlet passage 31 to be uncovered. When, however, the supply of 130

beverage in the dispensing chamber is normal, the beverage will raise the float and cause the valve 32 to rise against its seat so as to close said air-inlet passage.

- 5 The dispensing tank 5 is provided with a beverage outlet pipe 41, which may be led to the exterior of a casing surrounding this dispensing apparatus, or may be led to any distant point where it may be supplied with 10 a suitable faucet or other device for controlling the dispensing of the beverage.

Mounted on the hood 13 of the head 11 is a receiving chamber 42, which is preferably of cylindrical formation in cross section and 15 has a bottom 43 integral therewith and a removable cap or cover 44. This receiving chamber has its lower end externally screw-threaded and entered in the screw-threaded opening formed in the top wall of the hood 20 13; said top wall having an annular upstanding flange 45 which enters a downwardly opening groove formed in an overhanging annular extension on the outer face of the receiving chamber; a gasket 46 being placed 25 and tightened between the said upstanding flange and the top wall of said groove to provide a tight connection between the receiving tank and the head or cover member 11, of which said hood forms part.

30 The bottom of said receiving chamber has an escape tube 47 depending axially therefrom which is closed at its lower end and has an axial guide opening 48 in its bottom; and it is also provided with a plurality of 35 openings 49 in its peripheral wall. This escape tube is extended upwardly into the receiving chamber 42 a short distance and the upper end thereof serves as a valve seat 40 for a valve 50 adjustably arranged on a valve rod 51 extending downwardly through the guide opening 48 in the bottom of the escape tube and into an expansible or accordion-like member 52 which is open at its upper end and 45 may be termed an expansible chamber or bellows.

This expansible chamber or bellows, in the form shown, comprises a cylindrical circumferentially crimped, pleated, or fluted member having its upper end open and the upper end of its peripheral wall secured to the flange 20 extending inwardly from the upper end of the bellows or air-outlet chamber. The lower end of the expansible chamber or 55 bellows is closed by a disk 53, which serves as a rigid bottom for the same and the lower end of the valve rod 51 is screw-threaded or otherwise axially secured to said disk or bottom.

60 The removable cap or cover 44 has a depending internally screw-threaded rim 54 which surrounds and threadingly engages the externally screw-threaded upper end of the peripheral wall of the receiving chamber, and 65 it also has a sleeve extension 55 rising axially

therefrom in which the upper end of the valve rod 51 is guided.

Said valve rod is screw-threaded from its upper end downwardly a considerable distance and the valve 50, adjustable thereon, 70 is formed like the valve 32; it comprising a metallic or other solid head having a screw-threaded axial opening to receive the screw-threaded portion of the valve rod. Like valve 32 it has marginal clinch lips which 75 are bent against a leather or other suitable valve disk placed against the under side of said valve head; said lips serving to hold said disk firmly against said valve head. The said valve disk is of greater diameter than the 80 valve seat formed by the upper end of the escape tube 47, against which it is adapted to be seated. It will be apparent from the construction of the valve described and the manner of supporting it on the valve rod 51, that 85 it is easily adjustable on said rod.

Surrounding the valve 50 and the valve rod 51 within the receiving chamber 42, is an expansion spring 56, the lower end of which bears against the bottom wall of said chamber, while the upper end thereof bears 90 against an abutment 57 in the form of a disk adjustably threaded onto the valve rod 51. In this manner the tension of the spring may be varied and the force or pressure required to cause seating of the valve 50 against 95 its seat, governed accordingly.

Extending laterally from the receiving chamber 42 is a sleeve 58, the passage through which serves as an inlet for said receiving 100 chamber, or more broadly considered, for the dispensing apparatus; and it has arranged therein a conical sieve 59 to guard against entrance into the dispensing chamber of matter in suspension, or sediment, 105 from the storage or supply tank. Said sleeve 58 has a hose nipple 60 secured thereto by means of a sleeve nut 61, and to this nipple is secured one end of a hose 62 which leads to the storage or supply tank (not shown). 110

The storage or supply tank is usually filled with the beverage and delivered to the dealer or dispenser; the beverages so dispensed being usually in carbonated form maintained within the tank under high pressure. 115

Our dispensing apparatus may have its dispensing chamber or beverage container in any desired form, and the parts or mechanisms extending thereinto and surmounting 120 the same, may be varied in form and construction within the scope of the appended claims. The form of such parts and such mechanisms may depend more or less on the particular use to which our invention is put, and also to the particular formation or construction of the dispensing chamber or container 5.

It is to be understood that the dispensing chamber or container 5 can be disposed with 130

in any suitable form of outer casing in which, if desired, ice may be placed, or the interior thereof refrigerated in any approved manner, so that the beverage within the dispensing chamber will be kept at a low temperature.

The casing in which this apparatus may be placed may be in the form of a keg, a bottle, or represent any other object, or it may be constructed in box-like form without representing any particular object. We, however, have in mind in providing a cylindrical elongated dispensing chamber, to place the same within a large casing of bottle formation, which casing can be painted to represent, for example, a bottle of a particular brand of ginger ale; the coloring and painting of which would simulate bottles in which such particular brand of ginger ale is sold in cases, or otherwise; and when placed upon a counter, will be a novelty advertisement representing in large form, the usual bottles in which the ginger ale is sold for consumption at the home of the purchaser, or other places to which it may be carried or delivered from the dealer or distributor.

The operation of the device is as follows:

Assuming the dispensing apparatus to be connected with a supply or storage tank through the medium of the inlet-tube 62, and the beverage within said supply or storage tank to be maintained under a pressure upwards of eighty pounds per square inch, control of the passage of the beverage through said inlet-tube will be by means of a valve (not shown) within said tube or at the supply or storage tank.

Upon opening said valve, the beverage enters the receiving chamber 42 under the pressure maintained in the supply or storage tank, and by reason of the outlet of said receiving chamber, which is the upper open end of the escape tube 47, being uncovered, due to the action of the spring 56, which causes the valve 50 to be elevated from its valve seat, the beverage will flow from said receiving chamber into the escape tube 47, and from the latter it will escape through the openings 49 in said tube and enter the expansible or accordion-like chamber 52, completely filling the same. During this time the dispensing chamber 5 is maintained at atmospheric pressure, owing to the float 39 being in its lowermost position so as to unseat the valve 32, and thus establish, through the medium of the air-outlet chamber, connection with the atmospheric air.

When the beverage so supplied to said last-mentioned chamber fills the same, it will overflow and pass out of the upper open end of the expansible chamber 52, around the top of the air-outlet chamber 14, and pass down along the side of said chamber into the dispensing chamber 5. The beverage so delivered into said dispensing chamber will be

prevented from coming in contact with the valve cage 33, or from being carried out through said cage with the escaping air by the depending baffle flange 28. The air in the dispensing chamber, now above atmospheric pressure, will escape through the air-inlet passage 31 in the bottom of the air-outlet chamber 14, and pass out through the outlet opening 24 of said chamber. During such times the valve 32 is held unseated by the valve rod and float depending therefrom; but when the beverage within said dispensing chamber reaches a certain level, or said chamber is filled above said level, the float will rise and close said valve 32, thus preventing the escape of air from the dispensing chamber.

When the valve 50 is closed, the pressure within the dispensing chamber will approximate eight to ten pounds, or any other reduced pressure may be employed which will assure, upon opening of the dispensing pipe 41, the discharge of the beverage from the dispensing chamber at a pressure enabling the glasses or other vessels to be filled without undue sputtering, and without excessive force, such as would cause the beverage to be forced over the edge of the glass or other vessel without filling the same.

As the beverage is being dispensed from the dispensing chamber 5, and the level of the beverage lowers within said chamber, the float will lower accordingly and open the air-inlet passage 31 leading into the air-outlet chamber 14.

When the pressure within said dispensing chamber is built up to approximately eight or ten pounds per square inch, which occurs after closing of the valve 32, such pressure is exerted against the beverage contained in the expansible chamber 52, thus making it quicker acting than an unfilled expansible chamber, and by reason of the fact that the spring 56 is adjusted to be overcome by such predetermined pressure, the chamber 52 is expanded, causing the valve rod 51 connected to the bottom of said chamber to be drawn downwardly and the valve 50 to close the upper open end of the escape tube 47. With both valves 32 and 50 closed, the air within the dispensing chamber is maintained at the predetermined pressure of approximately eight or ten pounds, as the case may be, which is to be a desired pressure for beverages of this kind.

When the level of the beverage within the dispensing chamber lowers, the valve 32 is opened and causes reduction of the air pressure within said dispensing chamber, whereupon the spring 56 is brought into action and causes collapse of the expansible chamber 52. This results in the opening of the valve 50 within the receiving chamber and the admission of additional beverage under high pressure from the storage tank, where-

upon the action of supplying the dispensing chamber with the beverage is repeated in the manner stated. It will therefore be apparent that the dispensing chamber is provided 5 with the beverage automatically and intermittently in approximately the quantities discharged therefrom, and that the air within the dispensing chamber is under the desired pressure and in no manner dependent 10 upon the pressure of the air within the storage tank.

Having thus described our invention, what we claim is:

1. In a beverage dispensing apparatus, the 15 combination with a storage tank containing beverage under high pressure, of a beverage receiving chamber connected to said storage tank and having a depending escape tube in its bottom, an expansible chamber into which 20 said escape tube extends, an air-outlet chamber in which said expansible chamber is confined, said expansible chamber being open at the top, said air-outlet chamber having an air-inlet passage and an air-outlet passage, 25 a dispensing chamber into the upper end of which said air-outlet chamber extends and into which beverage overflows through the upper open end of said expansible chamber, a float-controlled valve adapted to close said 30 air-inlet passage when the beverage in said dispensing chamber reaches a predetermined level, a valve in said receiving chamber operatively connected with a movable wall of said expansible chamber, and a spring within said 35 receiving chamber adapted to normally hold said last-mentioned valve in open position to allow the beverage to pass from said receiving chamber into said expansible chamber under high pressure.

2. A beverage dispensing apparatus, comprising a dispensing chamber having a cover member closing its upper end, said cover member having a flat portion and a hood rising from said flat portion, an air-outlet chamber axially disposed in said dispensing chamber and having its upper end entering said hood, said air-outlet chamber being supported from the wall of said hood and spaced from the upper end thereof and having also 45 an air-inlet at its bottom and an air-outlet opening through said hood, an expansible chamber comprising an accordion-like peripheral wall secured at its upper end to the upper open end of said air-outlet chamber and a rigid bottom, a valve for said air-inlet, a float connected to said valve, a beverage receiving chamber mounted on said hood and having a depending escape tube extending into said expansible chamber, said escape tube having a portion extending upwardly 50 into said beverage receiving chamber serving as a valve seat and being provided be-

tween its ends with escape openings, a valve rod secured to the rigid bottom of said expansible chamber and extending upwardly through said escape tube into said receiving chamber, an abutment adjustable on said valve rod within said receiving chamber, a spring interposed between said abutment and the bottom wall of said receiving chamber, and a valve adjustable on said valve rod with- 70 in said spring. 75

3. A beverage dispensing apparatus, comprising a dispensing chamber, a controlling means for admitting the beverage under high pressure to said dispensing chamber including an expansible chamber, means allowing the escape of air beyond atmospheric pressure during the supplying of said dispensing chamber with the beverage including an air outlet chamber axially disposed in said dispensing chamber and having an air inlet at 80 its bottom and an air outlet at its upper end, said expansible chamber being disposed within said air inlet chamber and opening at its upper end, a valve for said air inlet, a float connected to said valve, and a baffle surrounding said valve to prevent the beverage from coming in contact therewith, said controlling means being governed by said predetermined pressure acting against said expansible chamber to shut off the supply of beverage to said dispensing chamber under high pressure. 90 95

4. A beverage dispensing apparatus, comprising a beverage dispensing chamber to which a beverage is supplied under pressure and from which it is discharged, and a pressure control device including an expansible chamber filled at all times with the beverage to be dispensed and located between the supply to said dispensing chamber and the discharge therefrom. 100 105

5. A beverage dispensing apparatus, comprising a beverage dispensing chamber to which a beverage is supplied under pressure and from which it is discharged, a pressure control device including an expansible chamber in the upper end of said dispensing chamber filled at all times with the beverage and from which the beverage is adapted to overflow into said dispensing chamber, an air chamber surrounding said expansible chamber provided with an air inlet and an air outlet, spring-actuated valve mechanism between said expansible chamber and the inlet of the beverage to said dispensing chamber functioning to admit the beverage to said expansible chamber, and means to close the air inlet of said air chamber governed by the beverage in said dispensing chamber. 110 115 120

In testimony whereof, we affix our signatures. 125
